UNITED STATES PATENT OFFICE.

FRANCIS G. GALE, OF WATERVILLE, QUEBEC, CANADA.

BED BOTTOM.

Application filed January 7, 1916, Serial No. 70,862. Renewed January 20, 1922. Serial No. 530,724.

To all whom it may concern:

Be it known that I, FRANCIS G. GALE, a subject of the King of Great Britain, residing at Waterville, Province of Quebec, Canada, have invented an Improvement in Bed Bottoms, of which the following description, in connection with the accompanying drawing, is a specification, like characters on the drawing representing like parts.

This invention relates to bed bottoms of that type comprising a plurality of vertically-disposed spiral springs which are connected together at top and bottom by tie-wires, and the object of the invention is to provide a novel bed bottom of this nature which is so constructed that a reduced number of springs can be employed without sacrificing anything in the way of strength or proper support for the mattress, in which the tie-wires are so arranged that the springs will be properly tied together with a minimum number of tie-wires, which will be squeakless and which has other advantages all as will be more fully hereinafter set forth.

In order to give an understanding of my invention I have illustrated in the drawings a selected embodiment thereof which will now be described, after which the novel features will be pointed out in the appended claims.

Fig. 1 is a plan view of a bed bottom embodying my invention;

Fig. 2 is a side view thereof;

Fig. 3 is a perspective view of a portion of the top of a bed bottom;

Fig. 4 is a sectional view taken through one side of the end turn of a spring showing the manner in which the tie-wires are secured thereto.

The herein-described bed bottom is of that type which comprises a plurality of vertical spiral or coil springs 1 that are connected at top and bottom by tie-wires which operate to hold the springs in their proper relative position and also assist in forming the top and bottom surfaces of the bed bottom.

In my novel bed bottom the tie-wires are arranged diagonally and those which extend in one direction are situated tangentially to the end turns of the spiral springs, while those which extend in the other direction are situated diametrically of the end turns of the spiral springs. Further, the tie-wires are welded together where they cross

each other and are also welded to the end turns of the coil springs 1 where they contact with said springs, thus making a practically integral and indestructible structure. The tie-wires which are arranged tangentially to the end turns of the coil springs are shown at 2 and those which are arranged diametrically thereof are shown at 3. The coil springs 1 are arranged in rows extending both longitudinally and transversely of the bed bottom, which arrangement results in diagonally arranged rows extending in each diagonal direction. The tie-wires 2 and 3 extend parallel to the diagonal rows. The tie-wires 3 extend centrally of each diagonal row, that is, said tie-wires pass over the centers of the spiral springs 1 in each diagonal row. The tie-wires 2 are arranged tangentially to the end turns 4 of each coil spring, and I propose to make the end turns 4 of such a size relative to the spacing of the coil springs that each tie-wire 2 will have a tangential arrangement with the end turns 4 of two rows of coil springs 1. In other words, the end turns 4 of each coil spring are of such a size that when a tie-wire 2 is placed in tangential relation to the end turns of one diagonal row, it will also have a tangential relation to the end turns of the next adjacent diagonal row. Each tie-wire 2, therefore, will tangentially engage the end turns 4 of two diagonal rows of springs 1, as clearly seen in Figs. 1 and 3.

The tie-wires 2 and 3 are connected to the end turns 4 of the cross wires in some suitable way, and to provide a rigid and strong structure, I will preferably electrically weld the tie-wires to the end turns 4 of the springs 1 at the points of engagement. I will also preferably electrically weld the tie-wires 2 and 3 together where they cross each other so that each end turn 4 of each spring 1 has two tie-wires electrically welded thereto on opposite sides thereof, as shown at 8 and 9 in Figs. 3 and 4. The end turn 4 of each spring 1 is thus firmly held in proper position by the tie-wires 2 and 3 at the two diametrically-situated points 8 and 9, and said tie-wires will hold the springs from lateral movement in any direction. These tie-wires, however, do not interfere with the yielding motion of the springs necessary to make a comfortable bed bottom.

In addition to the tie-wires 2 and 3 I also employ a peripheral binding wire 5 which extends around the periphery of the

bed bottom on both sides and is electrically welded to the ends of the tie-wires 2 and 3 and to the end turns 4 of the coil springs, as shown at 6.

5 My improved bed bottom is practically an integral structure because of the way in which the tie wires and peripheral wires are welded or joined to the end wires of the springs 1. A bed made in this way always 10 has the advantage that it is noiseless because there are no parts loosely in engagement with each other that can rub and thus produce a squeaking noise when weight is applied to the bed. All of the tie wires and 15 springs are welded together at points where they touch each other. Furthermore, the manner in which the tie wires are connected to the springs ensures that the strain on the wires will be evenly distributed, thus 20 enabling me to use a lighter and smaller wire than would otherwise be possible. This makes the bed bottom lighter in weight without sacrificing anything in the way of strength. The bed bottom is also reversible 25 in that both the top side and the bottom side are alike. This is an advantage because the bed bottom can be used either side up.

The arrangement of tie-wires 2 and 3 herein shown has the advantage that only 30 one tie-wire in each direction is required for each row of springs. The tie-wires 2 are disposed so as to have a tangential relation to the end turns of the springs, but because of the fact that each tie-wire 2 is connected 35 to two adjacent rows of springs there is only one tie-wire 2 for each row of springs, similarly there is only one tie-wire 3 for each row of springs. The number of tie-wires used is thus reduced to a minimum.

40 This arrangement has a further advantage that notwithstanding a minimum number of tie-wires are used, a relatively fine mesh is produced at each side of the bed bottom. This is due to the fact that the tie-wires 3 45 cross centrally the space between two adjacent springs in the row of springs extending parallel to the tie-wires 2 and the spaces between the springs are therefore divided up by the tie-wires so as to make a good support for the mattress.

A further advantage of this construction is that there are only two places at the end of each spring where the wires are fastened thereto. Since the tie-wires 3 engage the end

turns 4 of the springs at the points where 55 the tie-wires 2 have engagement therewith, it is only necessary to make two welds at each end of each spring in order to connect all the tie-wires to the springs.

I claim:

1. A bed bottom comprising a plurality of vertical coiled springs arranged in rows extending diagonally in both directions, a plurality of diagonal tie-wires for connecting the end turns of the coils, each of said 65 tie-wires being situated between two adjacent rows that extend in one direction, said rows being so spaced that the end turns of all the springs in the rows on each side of any tie-wires are tangential thereto, and other 70 tie-wires crossing the first named tie-wires at the points where they are tangential to the end turns of the springs and extending diametrically of said end turns, the crossing tie-wires being welded to the end turns of 75 the springs and to each other at the points where they cross the end turn of each spring having two of the first-named tie-wires welded thereto at two diametrically-opposite points and one of the last-named tie wires 80 welded thereto at both said points.

2. A bed bottom comprising a plurality of vertical coiled springs arranged in rows extending diagonally in both directions, a plurality of diagonal tie-wires on both the top 85 side and the bottom side of the bed bottom, each of said tie-wires being situated between two adjacent rows that extend in one direction, said rows being so spaced that the end turns of all the springs in the rows on 90 each side of any tie-wire are tangential thereto, and other tie-wires on both the top side and the bottom side of the bed bottom crossing the first named tie-wires at the points where they are tangential to the end 95 turns of the springs and extending diametrically of said end turns, the crossing tie-wires being welded to the end turns of the springs and to each other at the points where they cross, and a binding wire extending 100 around the periphery of the bed bottom at both the top and the bottom and being welded to the end turns of the springs and to the ends of the tie wires.

In testimony whereof I have signed my 105 name to this specification.

FRANCIS G. GALE.
